[57] **CLAIM**

I claim the ornamental design for a light ornament, as shown and described.

DESCRIPTION

FIG. 1 is a perspective view of a light ornament showing my new design;

FIG. 2 is a top view of the light ornament of FIG. 1;

FIG. 3 is a left side view of the light ornament of FIG. 1;

FIG. 4 is a front view of the light ornament of FIG. 1;

FIG. 5 is a rear view of the light ornament of FIG. 1;

FIG. 6 is a right side view of the light ornament of FIG. 1; and,

FIG. 7 is a bottom view of the light ornament of FIG. 1.

The broken lines showing a rear cover and feathers are for illustrative purposes only and form no part of the claimed design.
